TELESCOPIC ROTATING HINGE-BRACKET FOR IRONING-BOARDS.

1,174,218.

Specification of Letters Patent.

Patented Mar. 7, 1916.

Application filed February 10, 1915. Serial No. 7,453.

To all whom it may concern:

Be it known that I, HARRY D. YOUNG, a citizen of the United States, and a resident of Portland, county of Multnomah, and 5 State of Oregon, have invented a new and useful Improvement in Telescopic Rotating Hinge-Brackets for Ironing-Boards, of which the following is a specification.

My invention relates to ironing boards of 10 the type supported by a bracket fastened in a wall pocket, so that the ironing board is located so that it may be folded up into the wall pocket when not in use. But my bracket may also be fastened to the face of 15 a wall or in a cabinet fastened to the wall.

One of the main objects of my invention is to support the ironing board by means of a hinge-bracket, which may be longitudinally telescoped upon itself, so that when the 20 ironing board is in use, the hinge-bracket will permit it to be pulled out clear of the wall. The hinge bracket not possessing this feature would have a tendency to support the ironing board close to the wall when in 25 use, or else make the board too long when turned up against the wall, and if to be enclosed in a wall pocket or cabinet, would require such to be made of too great a height.

Another feature of my invention is; the 30 hinge-bracket is so constructed that the ironing board after having been pulled out, away from the wall, may then be adjusted at any convenient angle with respect to the bracket, and when so adjusted will be locked 35 in place.

Other features of my invention are the simplicity of construction and operation of my hinge-bracket.

The details of construction of my invention 40 are brought out in the accompanying drawings constituting a part hereof, in which—

Figure I shows a plan section of a wall pocket in which my improved hinge-bracket 45 is fastened. The ironing board is shown as pulled out, away from the wall, in order to render it more accessible, and it is also shown, by the dotted outlines, in this figure that when the ironing board has been pulled 50 out on its hinge-bracket, it may then be arranged in any convenient angle; Fig. II is a partial vertical sectional view on the line of the arrow II of Fig. III. The ironing board being shown as folded up on its hinge 55 in the wall pocket; Fig. III is a plan view

of my hinge-bracket, secured in the wall pocket as in Fig. I, but the ironing-board being removed so that the construction of the hinge-bracket may be more clearly seen; Fig. IV is a detail showing a vertical section taken approximately on the broken line IV of Fig. I. Fig. V is a fragmental plan view of the primary supporting member of my hinge-bracket, being the part fixed to the face of the wall or in the wall pocket; 60 Fig. VI is a section taken on the broken line VI—VI of Fig. V; and Fig. VII is a cross-section taken on the broken line VII—VII of Fig. V.

a, a represents the vertical studs of a wall, 70 and form the sides of a wall pocket, and *b* is a sill extending between said studs. On the inner side of each stud *a*, is a plate *c*, the lower end of which is made with a lateral lug *d*, and the rear part is provided 75 with a recessed portion *e*, adapted to serve as a bearing for the trunnions *g*, of the primary member *F* of my hinge-bracket. Such primary member *F* consists of a cross-bar *f*, the ends of which are provided with trunnion portions *g*, located to bear in the recesses *e*, of the plates *c*, as shown in Fig. IV, when the ironing board is lowered from the wall. Side arms *h* and center arms *i*, of the primary member *F* support the spider *K*, 80 consisting of spokes *j*, and a rim *k*. The arms *i*, are made of angle irons and spaced apart to provide the longitudinal slot *m*, which extends to the center of the spider, as shown in Fig. V. The rim *k* of the spider *K* is shaped 85 like an inverted L in cross-section, and the front half thereof is provided on its upper face with radially-located notches *n*. When the primary hinge member *F* is in its lowered position, so that the trunnions *g* will 90 bear in the recesses *e* of the plates *c*, the side arms *h* will bear on the lugs *d* of the plates *c*, thereby forming a two-point support for holding said hinge-member rigidly in horizontal position.

p, is the secondary member of my hinge-bracket. It is made in part of circular, or ring form, as shown in Fig. III, one side of the ring terminating in a cross-bar. The ring part and cross-bar are perforated to 105 receive screws *q* by which the ironing-board *o* is fastened on the secondary member. The latter is provided with a headed pivot-pin *r*, and a stud pin *t*, made at its extremity with a lateral toe *u*. Said pivot-pin *r* and 110

stud-pin *t*, slide in the slot *m* between the arms *i* of the primary hinge-member. The primary member is provided on its under side with stiffening ribs or flanges, as shown by the cross-sectional views Figs. VI and VII. The annular portions of the primary and the secondary members may be said to be turn tables.

Openings *v* are provided in the arms *i* at the juncture of the latter with the ring *k* of the spider *K*, and when the ironing-board has been drawn out, as shown in full lines in Fig. I, the pivot pin *r* will be located at the center of the spider *K*, and the stud-pin *t* will then be positioned for entering the openings *v*, thus permitting the ironing-board to be rotated on the pivot-pin *r*, and adjusted at any convenient angle as mentioned. When the ironing board is positioned at an angle, the toe *u* of the stud-pin *t*, will bear under the internal flange of the ring *k*, as illustrated in Fig. VII, in so doing combining with the pivot-pin *r* in providing a two-point support for rigidly holding the ironing board in horizontal position. The secondary hinge-member *p* is further provided with a lug *w*, on its under side (see Fig. IV) located to be inserted in any of the notches *n* of the supporting arm *k*, so as to thereby hold the board rigidly rotating on its pivot-pin *r*. By slightly lifting the ironing board, the lug *w* will be withdrawn from the notch *n* with which it is engaged, and the ironing board may then be adjusted in the angular position desired.

My hinge bracket may, of course, be used for supporting any kind of leaf or shelf instead of an ironing board.

The operation of my device is as follows: In Fig. II the ironing board is shown as folded up in the wall-pocket. When the ironing board is to be used, the first operation is to pull it down, whereupon it will take the position shown by the broken lines A in Fig. I. It is then to be pulled out longitudinally on the primary hinge member to its position shown in the full lines in Fig. I, at which point the stud pin *t* will be in registration with the notches *v*, which will permit the ironing board to be rotated horizontally in either direction. The broken lines B of Fig. I, show the ironing board as arranged in one of its most practical positions, which would be when it is arranged parallel to the wall so as to bring it in front of a window, adjacent to which the ironing board is located.

I claim:

1. In a hinge-bracket, the combination of a supporting member adapted for fixing to a supporting surface; a primary member hinged at one end to such supporting member, a secondary member movably seated on the primary member, means for holding the secondary member in parallel alinement

to the primary member at all points except at the outer end of said primary member, said means being adapted to permit the rotating of the secondary member on the primary member when the former has been moved to the outer end of the latter, and means for rigidly holding the secondary member in horizontal position after having been rotated on the primary member.

2. In a hinge-bracket, the combination of a supporting member adapted for fixing to a supporting surface; a primary member hinged at one end to such supporting member, a secondary member movably seated on the primary member, means for holding the secondary member in parallel alinement to the primary member at all points except at the outer end of said primary member, said means being adapted to permit the rotating of the secondary member on the primary member when the former has been moved to the outer end of the latter, and means for locking the secondary member against rotating on the primary member.

3. In a hinge-bracket, the combination of a supporting member adapted for fixing to a supporting surface; a primary member hinged at one end to such supporting member, a secondary member movably seated on the primary member, means for holding the secondary member in parallel alinement to the primary member at all points except at the outer end of said primary member, said means being adapted to permit the rotating of the secondary member on the primary member when the former has been moved to the outer end of the latter, means for locking the secondary member against rotating on the primary member, and other means for rigidly holding the secondary member in horizontal position after having been rotated on the primary member.

4. In a hinge-bracket, the combination of supporting means, a primary member hinged to said supporting means, said primary member being made with a turn-table at its outer end, and with a longitudinal slot extending to the center of such turn-table, a secondary member adapted to movably ride on the primary member; the secondary member being provided with a headed pivot-pin bearing in the slot of the primary member, the secondary member being further provided with a stud-pin having a laterally projecting toe, said stud-pin also bearing in said slot of the primary member; the latter being made with an opening located for permitting the movement of said stud-pin of the secondary member under the turn-table of the primary member, and means for locking the secondary member against rotating on the primary member.

5. In a hinge-bracket, the combination of supporting means, a primary member hinged to said supporting means, said pri-

mary member being made with a turn-table at its outer end, and with a longitudinal slot extending to the center of such turn-table, a secondary member adapted to movably ride on the primary member; the secondary member being provided with a headed pivot-pin bearing in the slot of the primary member, the secondary member being further provided with a stud-pin having a laterally projecting toe, said stud-pin also bearing in said slot of the primary member; the latter being made with stiffening ribs on its underside and having an opening through such stiffening ribs located for permitting the movement of said stud-pin of the secondary member under the turn-table of the primary member, and means for locking the secondary member against rotating on the primary member.

20 6. In a hinge-bracket, the combination of supporting means, a primary member hinged to said supporting means, said primary member being made with a turn-table at its outer end, and with a longitudinal slot extending to the center of such turn-table, the latter being provided with radially disposed notches on its upper face; a secondary member adapted to movably ride on the primary member, the secondary member being provided with a headed pivot-pin bearing in the slot of the primary member; the secondary member being further provided with a stud-pin having a laterally projecting toe, said stud-pin also bearing in said slot of the primary member, the latter being made with an opening located for permitting the movement of said stud-pin of the secondary member under the turn-table of the primary member, and a lug on the 40 secondary member adapted to be engaged with said notches of the turn-table of the primary member.

7. In a hinge-bracket, the combination of supporting means including upright members, each made with a notch located at its lower end, and a lateral lug located adjacent such notch; a primary member made with trunnion portions located for bearing in the notches of said upright members, said

primary member being made with a turn-table at its outer end, and with a longitudinal slot extending to the center of such turn-table, a secondary member adapted to movably ride on the primary member; the secondary member being provided with a headed pivot-pin bearing in the slot of the primary member, the secondary member being further provided with a stud-pin having a laterally projecting toe, said stud-pin also bearing in said slot of the primary member, the latter being made with an opening located for permitting the movement of said stud-pin of the secondary member under the turn-table of the primary member, and means for locking the secondary member against rotating on the primary member.

8. In a device of the character described, the combination of supporting means including upright members, each made with a notch located at its lower end, and a lateral lug located adjacent such notch; a primary member made with trunnion portions located for bearing in the notches of said upright members, said primary member being made with a turn-table at its outer end, and with a longitudinal slot extending to the center of such turn-table, the latter being provided with radially disposed notches on its upper face; a secondary member also made with a turn-table adapted to movably ride on the primary member, the secondary member being provided with a headed pivot-pin bearing in the slot of the primary member; the secondary member being further provided with a stud-pin having a laterally projecting toe, said stud-pin also bearing in said slot of the primary member, the latter being made with stiffening ribs on its underside and having an opening through such stiffening ribs located for permitting the movement of said stud-pin of the secondary member under the turn-table of the primary member.
